Primary Examiner — Calvin E Vansant*Assistant Examiner* — Kaitlyn G Wiltshire(74) *Attorney, Agent, or Firm* — Harvest IP Law, LLP(57) **CLAIM**

The ornamental design for a machine center as shown and described.

DESCRIPTION

FIG. 1 is a perspective view;

FIG. 2 is a front view;

FIG. 3 is a rear view;

FIG. 4 is a left side view;

FIG. 5 is a right side view; and,

FIG. 6 is a top view.

The machine center of the present design is a large-sized heavy item, and the bottom view forms no part of the claimed design and is therefore omitted.

The broken lines depict portions of the machine center and form no part of the claimed design.
